Patented Apr. 24, 1917.

UNITED STATES PATENT OFFICE.

HERMAN G. PAPE, OF NEW YORK, N. Y., ASSIGNOR TO RALPH A. SCHOENBERG, OF NEW YORK, N. Y.

SOCKET.

REISSUED

1,223,417.

Specification of Letters Patent. Patented Apr. 24, 1917.

Application filed June 23, 1916. Serial No. 105,514.

To all whom it may concern:

Be it known that I, HERMAN G. PAPE, of New York city, in the county and State of New York, have invented a new and useful 5 Socket, of which the following is a specification.

One feature of my invention consists in arranging the switch mechanism in the circuit so that when the switch is open the 10 screw shell is electrically isolated thus eliminating liability of injuring a person while handling the device when the latter is wet.

Another feature is a bracket having open slots to guide the slide and to permit ease 15 of assembling and disassembling, the slide being preferably held against sidewise movement by the same spring which connects the slide and the movable contact.

Another feature consists in having the 20 bracket provide a supporting surface for the movable contact member so that the latter will be maintained in proper operative position and held against twisting or canting.

Another feature of my invention consists 25 in providing a lubricant well or pocket adjacent to one or more of the fixed contacts of the switch mechanism.

Other features of my invention will be 30 pointed out below.

In the accompanying drawings:

Figure 1 is a side elevation of a socket constructed in accordance with my invention, the outer casing or shell being omitted;

Fig. 2 is a plan view of the inner side of 35 the outer section of the porcelain body hereinafter described;

Fig. 3 is a sectional view on line 3—3 of Fig. 1;

Fig. 4 is a section on line 4—4 of Fig. 3;

Fig. 5 is an elevation of the end of the 40 socket opposite to that shown in Fig. 3;

Fig. 6 is a partial section on line 6—6 of Fig. 3;

Fig. 7 is a detail hereinafter described;

Fig. 8 is an elevation of the upper end of 45 a lamp socket embodying the mechanism shown in Fig. 1.

The lamp socket herein shown comprises 50 a body made up of two sections 1 and 2 of porcelain or other suitable insulating material which are connected by a pair of metallic struts 3 and 4. On this body 1—2 is mounted a circuit controlling switch which

is the same in its general principle of construction and mode of operation as the switch shown and described in my co-pending application Serial No. 87,102, filed March 27, 1916, and also a metallic screw shell 5. The usual metallic housing for the 55 body 1—2 and parts carried thereby together with its lining of insulating material is not shown in Figs. 1 to 7 of the drawings but is constructed and applied in the ordinary fashion.

The strut 3 is fastened at one end to the body section 1 by means of screws 6 while the opposite end of said strut is made with a laterally extending arm 7 occupying a notch 8 formed in body section 2 and fastened to 60 the latter by means of a screw 9. This strut 3 is tapped to receive a screw 10 by means of which the end of one of the lead wires of the circuit is fastened thereto.

The strut 4 is fastened at one end to the 65 body section 1 by means of a screw 11 and at its opposite end to the body section 2 by means of a screw 12, said screw 12 also serving to fasten in position on said body section the usual center contact 13. This strut 4 is 70 also tapped to receive a screw 14 by means of which the end of the other lead wire of the circuit is fastened to said strut.

The body section 1 is formed upon its periphery with two notches 15 and 16 through 75 which the lead wires extend to the screws 10 and 14.

Between the two body sections 1 and 2 and fastened to the latter by means of a pair of screws 17 is a bracket 18 comprising two 80 posts 20 formed with open slots 19 within 85 which is slidably mounted the actuating member 21 of the switch mechanism. Actuating member 21 is connected by a spring 22 with a movable contact 23 pivotally connected near its middle with the bracket 18 by a stud 24. This contact member 23 cooperates with the head of screw 9 and also with the head of a screw 25 extending 90 through body section 2 and having threaded 95 engagement with a nut or block 26 which clamps the flange 27 of screw shell 5 to said body section. The screw 25 is arranged upon the opposite side of the pivot stud 24 from screw 9 and the movable contact member 23 100 when swung on stud 24 moves into and out of engagement with the two screws 9 and 25 simultaneously. As additional means for 105

securing the screw shell 5 to the body section 2 I provide another screw 27 extending through said body section and having threaded engagement with a nut or block 28 which also clamps the flange 27 of shell 5 to said body section.

When the movable contact member 23 is in engagement with the two screws 9 and 25 the circuit is closed and is traced as follows:—From strut 3 with which one of the lead wires is connected by screw 10, through arm 7, screw 9, member 23, screw 25, to screw shell 5; thence through the lamp mounted in said shell back to the center contact 13 from which it continues through screw 12 to strut 4 with which the other lead wire is connected by means of screw 14. It will thus be seen that each screw 9 and 25 serves as a fastener, one holding the strut 3 to body section 1 and the other holding the screw shell 5 to said body section, also as a stationary contact, and as a conductor.

As shown in Fig. 4 the spring 22 comprises a coil 29 from which project two legs 30 and 31. The leg 30 extends through a hole in the removable contact 23 and beyond the inner side of the latter into a slot 32 formed in the base of bracket 18 concentric with stud 24, while the leg 31 extends around and under actuating slide 21 with the extremity thereof occupying a hole 33 formed in said slide.

The stress of spring 22 serves to yieldingly hold the actuating slide 21 at the limit of its movement in one direction or the other with one of a pair of stop lugs 34 provided on said slide, in engagement with bracket 18, and to yieldingly hold movable contact 23 at the limit of its movement in one direction or the other, the swinging movements of said member in both directions being limited by its engagement with the posts 20 of bracket 18. The spring 22 also serves the important function of holding slide 21 within the slots 45 against sidewise displacement.

The ends of the actuating slide 21 are provided with buttons 35 and 36 of insulating material which may be differently colored so that their position will serve to indicate 50 "open" and "closed" condition of the switch mechanism.

A feature of my present invention of practical importance consists in providing a lubricant well 37 adjacent the head of each screw 9 and 25, each well being herein shown as an annular groove surrounding the head of its screw and filled with a lubricant such as grease. When the circuit is closed the current warms the screws 9 and 25 thus softening the grease while the quick snappy movements of the contact 23 in approaching and leaving the heads of screws 9 and 25 tend to suck the softened grease up onto the tops of said heads thus maintaining the 65 wearing and contacting surfaces of the

screws and member 23 well lubricated but without likelihood of making the contact surfaces sticky.

By having the slide 21 arranged between the two legs 30 and 31 of the spring 22 and carrying the leg 31 around and under said slide, not only is the mechanism made more compact than heretofore, but the leg 30 may be made to engage the member 23 nearer the pivot of the latter which improves the action 75 of the spring and of the member 23.

It is customary to form slots 40 to receive the push buttons 35 and 36 in the metallic housing 41 within which the parts described are arranged in order that the body 1—2 80 with its screw shell may be slid into said housing, and another feature of my invention consists in providing the body section 1 with a pair of diametrically opposite lugs 38 and 39 which occupy said slots 40 to close 85 the outer ends of the latter and hold the body 1—2 against rotative displacement within the housing 41 thus relieving the push buttons of this duty.

The described mode of lubricating the 90 switch mechanism has the advantage that the contacts are not overdosed with lubricant and the latter can not become dry and coat the contacts and thereby act as an insulation as heretofore. In time vaseline and 95 other lubricating material become sticky and dry and gummy, the result being that the electrical contact becomes poor and sometimes spoiled entirely and by sinking a groove adjacent to the contact and putting 100 lubricant in the groove, the lubricant will when the switch is operated draw up or suck up the lubricating material in moderate quantities as desired and thereby keep the contact surfaces continually lubricated. 101

What I claim is:

1. A socket comprising a screw shell; a movable contact; and a fixed contact co-operating with the movable contact, said fixed contact being directly connected to the 11 shell.

2. A socket comprising a body of insulating material; a screw shell mounted on said body; a movable contact; and a fixed contact co-operating with the movable contact, said fixed contact being directly connected to the shell. 11

3. A socket comprising a body consisting of two separated sections of insulating material; two struts connecting said sections; 12 means for connecting one of the lead wires to one of said struts and the other lead wire to the other of said struts; switch mechanism mounted between said sections, and comprising a stationary contact which also 12 serves to fasten one of said struts to one of said sections.

4. A socket comprising a body consisting of two separated sections of insulating material; two struts connecting said sections; 13

- means for connecting one of the lead wires to one of said struts and the other lead wire to the other of said struts; switch mechanism mounted between said sections, and comprising a pair of stationary contacts, one of said contacts serving to fasten one of the struts to one of said sections and a screw shell fastened to one of said sections by the other of said stationary contacts.
- 5 10 5. A socket comprising a body consisting of two separated sections of insulating material; two struts connecting said sections; switch mechanism mounted between said sections and comprising a stationary contact; and a screw shell fastened to one of said sections by said contact.
- 15 20 6. A socket comprising a body consisting of two separated sections of insulating material; conducting means holding said sections together; and means fastening said holding means to said sections including a stationary contact; and a movable contact coöperating with said stationary contact.
- 25 30 7. A socket comprising switch mechanism having in combination an actuating slide; a bracket to guide the slide longitudinally and formed to prevent transverse movement of the slide in one direction but open to permit transverse removal in the opposite direction; a movable contact member; and a spring actuated by said slide and actuating said member, said spring preventing transverse movement of the slide in said opposite direction when the switch is assembled.
- 35 8. A socket comprising switch mechanism having in combination an actuating slide; a bracket formed with a pair of open slots extending transversely of said slide and guiding said slide in its longitudinal movement; a movable contact member; and a spring actuated by said slide and actuating said member, said spring preventing transverse movement of said slide in the direction of the open ends of said slots.
9. In a socket the combination of a body 45 of insulating material; switch mechanism mounted thereon comprising a movable contact having a flat portion, an actuating slide for said contact, and a bracket secured to said body on which said contact and slide are mounted, said bracket being provided with a flat portion which engages the flat portion of the movable contact during movement of the latter and supports said contact against tilting.
- 50 10. In a socket the combination of a body of insulating material; switch mechanism mounted thereon comprising a movable contact having a flat portion, an actuating slide for said contact, and a bracket secured to 55 said body on which said contact and slide are mounted, said bracket being provided with a flat portion which engages the flat portion of the movable contact during movement of the latter and supports said contact against tilting and provided with guiding portions for said slide.
11. A socket comprising a body consisting of two separated sections of insulating material; two struts connecting said sections; 60 switch mechanism mounted between said sections and comprising a stationary contact; and a screw shell fastened to one of said sections by said contact.

HERMAN G. PAPE
